CLAIM

The ornamental design for a hemostasis device, as shown and described.

DESCRIPTION

FIG. 1 is a perspective view of a hemostasis device showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is a front view in a state where a balloon is deflated;

FIG. 9 is a right view in a state where a balloon is deflated;

FIG. 10 is a perspective view in a state where a balloon is deflated; and,

FIG. 11 is a reference view showing a usage state.

The oblique shadings shown in FIGS. 1 to 11 represent transparent or translucent portions of the claimed design.

The broken lines shown in FIGS. 1 to 11 represent portions of the hemostasis device and form no part of the claimed design.

The broken lines shown in FIG. 11 represent environments and form no part of the claimed design.

The dash-dot break lines indicate that the appearance of any portion of the hemostasis device between the dash-dot break lines forms no part of the claimed design.
